(57) **CLAIM**

The ornamental design for a wheel for an automobile, as shown and described.

DESCRIPTION

FIG. 1 is a front side perspective view of a wheel for an automobile;

FIG. 2 is an enlarged partial front side perspective view thereof; and,

FIG. 3 is a front view thereof.

The broken lines in the drawings illustrate portions of the wheel for an automobile that form no part of the claimed design.

1 Claim, 3 Drawing Sheets

FIG. 1

FIG. 2

FIG. 3
